 15, 1932

10 Claims. (Cl. 179—171)

The present invention relates to radio signaling systems and more particularly to systems of that character embodying electric discharge devices as audio frequency amplifiers and modulators, being a division of my copending application Serial No. 586,874, filed January 15, 1932, and entitled Radio signaling system.

Since the early use of electric discharge devices or vacuum tubes in the broadcasting art, the demand for higher output power from audio frequency amplifier systems has steadily increased, in both radio receiving and transmitting apparatus.

In radio receiving apparatus, as is well known, the demand for higher power output occurs chiefly in connection with the output stage of the audio frequency amplifier, while in transmitting apparatus it occurs both in connection with the power amplifier and in connection with the modulator, used in conjunction with the power amplifier, to apply the modulating or audio frequency signal to the carrier wave.

This demand for higher audio frequency power has heretofore been met chiefly by the development of tubes having a higher plate or anode dissipation and a lower plate or anode resistance, and the use of these or available standard tubes in balanced or push-pull relation and in multiple, both in radio receiving and amplifying apparatus and in transmitting apparatus. This expedient has the disadvantage that it involves a multiplicity of tubes and associated apparatus, with corresponding complication and cost. This is particularly true in connection with transmitters arranged for substantially 100 per cent modulation and having appreciable power output, for the reason that the power requirements for a suitable modulator therefor is of a corresponding magnitude and cost.

When the antenna or output current of a transmitter is caused to fluctuate according to a modulating wave of any shape, the average antenna current may remain the same, but the effective value of the current increases, therefore, increasing the average power input to the antenna. This increase in antenna power must be supplied (a) by the modulators employed, (b) by an equivalent increase in power, (c) by an increase in the plate current to the power amplifier tubes, or, (d) by an increase in the average efficiency of the power amplifier tubes.

It is generally conceded that the increased power may best be obtained by method (a) above, in supplying the increased power in the form of audio frequency power to the anode or plate cir-

cuit of the radio frequency power amplifier. However, this has heretofore involved the use of tubes of higher rating, adapted to carry the larger modulator power output. Therefore, in meeting such increased power requirements, modulators heretofore and at present may often include a plurality of high power tubes connected in balanced and in multiple relation, with attendant high cost of operation as well as initial cost.

It is, therefore, an object of the present invention to provide an improved modulator adapted to economically supply relatively large amounts of audio frequency power with electric discharge devices of normal power rating and without employing an excessively large number of such devices as has heretofore been necessary.

It is well recognized that 100 per cent modulation is the most economical degree of modulation. This is for one reason, among others, that the higher percentage modulation permits the use of a transmitter of lower power for the production of the same signal strength at a given distance from the transmitter. Furthermore, the higher modulated signal is subject to much less interference.

For 100 per cent modulation it will be seen that in a high power transmitter employing a class "C" amplifier, a relatively large amount of audio frequency power is required from the modulator. It is a common practice at present to supply the modulating power to such amplifiers by a modulator having a plurality of electric discharge amplifiers connected in multiple or balanced relation, the number of such devices being in any case relatively large and depending upon the amount of power required from the modulator. As has been shown heretofore, the amount of power required for modulation purposes may be in the order of the power output of the output amplifier.

The present invention relates more particularly to the class "B" type of amplifier as the output stage of an audio frequency amplifier unit for signaling systems, and has for a further object to provide an improved audio frequency electric discharge amplifier or modulator of that type from which a higher undistorted output power may be obtained at audio frequencies than has heretofore been obtainable by known means or arrangement of electric discharge devices, and which is adapted to supply large amounts of audio frequency power sufficient to modulate a class "C" or a class "B" output amplifier for a transmitter of relatively high power, to any desired degree of modulation.

In the class "B" of amplifier, the output or power tubes are biased to essentially anode current cut-off and when the input electrodes or grids are properly biased and driven by signal currents to substantially zero bias swing, the first three of the above conditions are satisfied to a fair degree. However, like the class "A" amplifier, this type requires relatively low audio frequency power from the signal source to operate it, and the input system thereto may be the usual relatively high resistance type. An amplifier of the class "B" type, however, does not in itself satisfy all requirements, and must be of the type described and claimed in the application of which this is a division. As has been pointed out this requires that the amplifier tubes be arranged in balanced relation to each other and that the input and output impedances of the circuits connected therewith must be lower than the lowest internal operating impedances of the tubes whereby the tubes may be operated to the limit of their space charge or emission.

It is, therefore, a further object of this invention to provide an improved audio frequency amplifier arranged to operate the electric discharge devices or tubes therein in such a manner and to such limits that they may supply an audio frequency output relatively higher than the normal output of the same electric discharge devices or tubes with the same anode voltage, with a lower average anode dissipation, and with no serious effects upon their life. Thus, in accordance with the invention, the usual requirements for higher plate or anode dissipation and higher anode voltages, both of which are costly in tube construction and in the matter of the supply of operating potentials, are entirely obviated.

In accordance with the invention there may be provided an audio frequency amplifier by which a relatively high audio frequency output, for example of five to ten times the usual or normal output, may be obtained without increasing the size, rating, or number of electric discharge devices employed therein, and without increasing the anode potential or anode dissipation.

An amplifier of this type may be used as a source of high audio frequency power for plate modulation of a transmitter as hereinbefore described, and may be applied to any signaling system requiring a relatively high audio frequency output, with a minimum of equipment.

Because of the class "B" type of operation, a varying load is placed upon the anode power supply for an improved amplifier and modulator embodying the invention; and accordingly it is a further object of the invention to provide means in connection with the source of anode or plate current supply, whereby fluctuations in load are prevented from appreciably affecting the voltage regulation of the source.

The invention will be better understood from the following description when taken in connection with the accompanying drawings, and its scope will be pointed out in the appended claims.

In the drawings, Figure 1 is a circuit diagram of an audio frequency amplifier embodying the invention;

Figs. 2 and 3 are curve diagrams illustrating operating characteristics of the amplifier shown in Fig. 1;

Fig. 4 is a circuit diagram of a modulator embodying the invention as applied to a broadcast transmitter having a high power output amplifier of the class "C" type; and

Fig. 5 is a circuit diagram of an alternating current amplifier or modulator embodying the invention and applied to a short wave transmitter system.

Referring to Fig. 1, an improved class "B" 5 audio frequency amplifier embodying the invention is shown. This amplifier includes an output stage 10 and a driver stage 11 therefor, which are so coupled and controlled, that by means of an electric discharge amplifier or vacuum tube 12 of 10 relatively low power output in the driver stage, which may be of the class "A" type for example, the output stage may be driven substantially to the limit of the emission or space charge of the electric discharge devices or tubes therein for 15 maximum audio frequency power output. For a given power output, the latter tubes also may be of normal power rating as will be seen hereinafter.

The amplifier 12 receives audio frequency signal voltage from any suitable source such as input terminals 13 which are connected with it through a suitable input or grid circuit 14, whereby audio frequency signal potentials applied to said terminals or to the input of the 25 amplifier, are amplified by the device 12 and through its output or anode circuit indicated at 15, are applied to the output stage 10.

The output amplifier stage consists essentially of two tubes 16 and 17 connected in push-pull or 30 balanced relation between push-pull input and output coupling devices 18 and 19 respectively, and biased for class "B" operation, as indicated. The grid bias supply indicated is preferably of 35 relatively low direct current resistance. The output stage is provided with a suitable anode voltage or plate supply source as indicated in the drawings. The anode voltage supply source should have good voltage regulation under wide 40 load variations, as it should be understood that the load current increases with an increase in the amplitude of applied signal voltages in this type of amplifier.

The output stage is provided with an input circuit or system, including the coupling device 45 18 and the output circuit 15 of the driver stage, having a relatively low impedance in itself, whereby the signal voltage is permitted to carry the grids of the tubes 16 and 17 therein, far into the positive range of operation, without a reduction of the available signal voltage and hence 50 distortion, because of the impedance drop in such input circuit or system, and without excessively loading the driver stage.

The driver or first stage of the amplifier is 55 preferably but not necessarily, transformer coupled to the output stage. In the present example, device 18 is a transformer having a step down ratio from a primary winding 20 in the anode circuit 15, to each side of the secondary winding 21, which is included in an input or grid circuit 22 for each of the output tubes. It should again be noted that two tubes in balanced or 60 push-pull relation are preferred for substantially distortionless class "B" operation in an audio frequency amplifier.

The step down ratio of the coupling device or 65 input transformer 18 for the output stage is arranged to permit a relatively low reflected 70 impedance, over from the anode or output circuit 15 of the driver stage, in each half of the input or grid circuit 22 of the amplifier 10, in series therewith. Therefore, when the grids of the tubes 16 and 17 are driven into the positive 75

range, the low effective input resistance permits grid current to flow without seriously affecting the shape of the signal or input voltage wave as applied at the input terminals 13 of the amplifier.

5 The impedance ratio of the input coupling means, furthermore, is such that the current requirements of the grid circuit 22 are met without overloading the driver stage 11 and introducing distortion, and, is further of an order such 10 that the anode circuit impedance of the driver stage reflected over into each half of the grid circuit 22 of the output stage 10 in series therewith, is substantially less than the grid to cathode impedance of the electric discharge device 16 or 15 17 in the output stage connected with that half of said grid circuit, when drawing maximum grid current through said circuit.

The output or power amplifier devices 16 and 17 are preferably of the type having a high amplification factor, and a higher, rather than a lower, internal impedance. Like the device 12 shown in the driver stage, they are illustrated in the present example as being of the usual three-element type of vacuum tube, although other 20 types of electric discharge devices may be used. In general, these tubes are of the ordinary audio-frequency amplifier type.

In any case, the output tubes 16 and 17 are arranged to be operated in accordance with class 30 "B" operation, that is, the control electrodes or grids are biased to substantially anode or space-current cut-off as indicated by the legend in the drawings, Fig. 1.

The bias source is located in the grid circuit 22, 35 and is common to both devices 16 and 17. In the present example, the input or grid circuit 22 for devices 16 and 17 is provided by a winding or impedance 21, this being the secondary of the coupling device or transformer 18, and is mid-tapped 40 as indicated at 24 for application of the biasing potential, in the usual manner for push-pull circuits.

The load connected with the output stage is also arranged to have a relatively low impedance 45 with respect to the internal impedance of the output stage. To this end, the output circuit of the power stage is arranged to have a low impedance with respect to the internal or plate impedance of the electric discharge devices 50 therein.

The output circuit of the power or output stage 10 includes a balanced output or anode circuit 25 for devices 16 and 17, a source of load therefor indicated by output terminals 26, and the output 55 coupling device or transformer 19 which is interposed between the circuit 25 and the load, as an impedance transforming means.

The anode or operating potentials for the devices 16 and 17 are applied through a mid-tap connection 28 on the primary winding 27 of the output transformer or coupling device, and the anode circuit 25, in the usual manner for push-pull amplifiers. The plate or anode supply source which may be connected between the cathodes 60 and the tap 28 should, as indicated, have good regulation for the reason that in operation the devices or tubes 16 and 17 draw a varying load current in response to changes in the impressed signal voltage.

70 In accordance with the invention, therefore, the grid or input circuit per se as distinguished from the entire input circuit or system, of the power amplifier or output stage, must be of low resistance and the input circuit as a whole must 75 be of low impedance, so that the power or cur-

rent requirements of the tubes through the grid circuit may be met without seriously distorting the wave shape of the signal applied to the driver stage, and the reflected load back into the output circuit, or the output circuit impedance, 5 must be kept low with respect to the internal impedance of the output tubes in order that the tubes may be driven to the limit of their emission or space charge, without distortion in the plate circuit.

10 The output power is limited by the plate dissipation, the maximum direct current to the plate, or the maximum allowable grid voltage swing within the distortion limits. If the grid voltage swing limits the output because of distortion, it does so by swinging in a positive direction until it approaches the minimum instantaneous plate voltage. When the two voltages approach each other, the direct current of the grid rises very rapidly with any increase in grid 20 voltage swing. The plate or anode current swing for a given excitation depends upon the load resistance in the plate circuit. The load resistance, then, bears a very important relation to the tube loss, the maximum power output and the power 25 required to drive the grid, as will be seen hereinafter.

30 Referring now to Fig. 2, 29 and 30 are plate or anode-current, grid-bias curves for tubes 16 and 17 respectively, of Fig. 1. The curves are plotted with respect to a grid-bias scale or zero plate current line 31, and an ordinate 32 representing plate current and grid current scales. The curve 29 is plotted from data obtained by 35 varying the applied grid potential and reading the corresponding anode current for one tube such as tube 16, in the circuit 25 of Fig. 1. The plate current curves are taken with load, that is with a load at 26 reflected over in series with one tube in the plate circuit 25.

40 The zero bias line for curve 29 is indicated at 33 and it will be noted that the normal anode current for class "B" operation is indicated at 34 through which is drawn the normal negative bias line 35. It will also be noted that the negative bias 45 is such that the point 34 on the curve 29 is substantially at zero or cut-off for the anode current. In response to applied signal potentials, the anode current increases along the line 29 to a maximum point such as the point 36 for example. The total 50 grid swing for such operation is indicated at 37, which includes the negative range 38 and a considerably larger positive range 39. This is the grid or input signal voltage swing, A, for the tube 16.

55 It will be noted that the operation of each tube is carried far into the positive range and that after the zero bias at line 33 is passed, the grid begins to draw an increasing amount of grid current indicated by the curve 40, a point of maximum slope on which is indicated at 41.

60 The lower curve 30 for the tube 17, is the same as the upper curve 29 except that it is reversed and shifted along the bias line 31 until the curves 65 29 and 30 coincide as nearly as possible to a line 42 drawn through the straight portion of the upper curve 29. The bias potential indicated at the point 43 through which the straight line 42 passes in crossing the zero plate current line or the grid bias line 31, is the proper normal negative bias 70 potential to use for the two tubes 16 and 17 having characteristics substantially as shown.

75 If the tubes or electric discharge devices are not similar, or if the anode supply voltage is slightly different from the values indicated by 75

the curves shown, the bias may be adjusted until the anode current is obtained as indicated by the curves.

The relation of the plate or anode current curves 29 and 30 of Fig. 2 is an indication of the operation of devices 16 and 17 respectively in the circuit shown in Fig. 1. When the grid of one tube is driven in a positive direction from its normal negative bias value, the plate or anode current of that tube increases with the swing, and flows through one-half of the primary winding of the output device 19. The output voltage for this half cycle bears substantially a linear relation to the input voltage to the amplifier. At the beginning of the next half cycle the above tube becomes idle because its grid becomes more negative and the other tube functions in a manner similar to the first except that the anode current flows in the other half of the output winding of the device 19, and the output voltage is therefore 180 degrees out of phase with the first half wave.

These two output waves will thus unite to form a wave similar to the input signal wave, with no distortion, if the plate current and grid voltage have a linear relation substantially as shown in Fig. 2. This relation is substantially linear as will be seen by the similarity between the curves 29 and 30 and the straight line 42 drawn through them.

It should be noted that the input coupling device or transformer 18 delivers current to the grids of the output tubes from only one side of the secondary at any particular instant, which must be considered in the design of this device.

If the signal swings to the right, as indicated, in Fig. 2, from the zero center line or bias line 35 common for both tubes, the plate current 29 of the tube 16 which may be designated as I_{bA} , increases, and as the grid becomes positive, grid current designated as I_{cA} , flows according to curve 40. As the signal reverses, I_{bA} decreases and as it passes the common bias line, I_{bA} becomes zero and plate current I_{bB} of the other tube 17 increases according to the curve 30. Therefore, each tube functions over one-half cycle, while the other is practically idle.

It should also be noted that the entire output power must be transferred from only one side of the output transformer primary during each half cycle. Therefore, the load impedance applied at 26, which either the tube 16 or the tube 17 is working into, is calculated as if only one tube is supplying the total power from one side of transformer primary 21, but in calculating plate dissipation, each tube functions for one-half the time so that the total plate loss is divided between the two tubes.

Referring now to Fig. 3, the alternating current component of the anode or plate current I_p , the alternating current plate voltage E_p , and the alternating signal voltage E_s , applied to the grids of the output tubes are plotted as ordinates against time, in curves 44, 45, and 46 respectively. The curve 45 for the plate voltage is shown with respect to the normal applied anode or plate potential E_b indicated by a line 47, while the cathode potential or zero axis is indicated by a line 48. The normal negative grid-bias potential with respect to the cathode line 48 is indicated by a line 49, about which as an axis, the curve 46 is drawn. One-half cycle of the alternating current component of the alternating current anode or plate current I_p is shown and is drawn with respect to a line 50 corresponding to the normal anode or

plate current indicated in Fig. 2 at point 34 on curve 29.

These curves show the relation between the various instantaneous values of the alternating current components of the anode current, anode voltage, and grid voltage.

In providing this amplifier arrangement, in the input circuit there is interposed between the grid circuit of the output stage and the output circuit of the driver stage, a coupling means such as a step-down transformer so designed that a reflected series impedance R_s , over from the preceding driver stage, is of a lower value than the impedance of the grid circuit between the grid and cathode of each tube in the output stage, 15 when said grid is at a maximum positive potential and drawing a maximum grid current.

At the same time, in the output circuit, a coupling means such as a transformer, is provided whereby the reflected load R_p back into the 20 plate circuit of the output stage is of a lower value than the internal impedance r_p of each of the output tubes, in series with the plate circuit.

Furthermore, the direct current resistance of 25 the grid or input circuit of the output stage must be relatively low, together with the source of bias potential, to prevent distortion, because of voltage drop in the elements of the circuit. Also, in the output circuit of the output stage, the 30 anode potential supply must have good regulation.

It will be noted that a low impedance grid circuit, as a part of the input circuit for the output stage, is provided without resorting to artificial loading means such as a shunt resistance, in connection with the grid circuit. The loading effect of such resistance upon the grid circuit and upon the driver stage, would seriously 40 introduce distortion or introduce practical limits into the design, whereby the desired operating characteristics would not be obtained. Chief among the disadvantages of such a circuit would be the lowering of the applied signal voltage to 45 the output stage and additional load upon the driver stage.

Assuming that an applied potential of 2000 volts or E_b is provided as indicated in Fig. 3, the 50 1300 volts or E_{pm} will leave an instantaneous minimum potential E_{bm} on the plate of 700 volts. As hereinbefore explained, this last named voltage may be and preferably is, the minimum anode potential necessary to maintain a maximum flow of plate current as determined by the space 55 charge of the particular tube. At the same time, the impedance of the output circuit should be and preferably is such that a maximum plate current I_{pm} may flow with minimum instantaneous applied potential. It will thus be seen, as 60 hereinbefore pointed out, that the power output is affected by the load impedance and by the space charge of the tubes employed. It is also affected by the emission limits of the tubes, and the load impedance must be such that the plate 65 dissipation of the tube is not exceeded.

The load impedance on each tube of the balanced tube arrangement, during the time it works, must be relatively low in order to obtain a desired power output, while at the same time 70 it must be high enough to prevent a plate dissipation beyond the rating of the tube employed. The load resistance is thus chosen that for a maximum grid excitation the normal plate dissipation may be reached and the minimum in- 75

stantaneous plate voltage E_{bm} , Fig. 3, is sufficiently high to prevent anode or space current limitation, that is, to permit I_{pm} to flow against the space charge and also to permit the plate current to reach values near the limit of the emission of the tubes.

By way of example, it has been found that it is possible to use a one k. w. output tube with class "C" operation for a one k. w. broadcast transmitter, and modulate the plate circuit to 100 per cent by two 350 watt tubes as a class "B" audio frequency amplifier of this type, whereas otherwise with existing systems it is necessary to use a 4 k. w. tube operating as a class "B" high frequency amplifier for a one k. w. station with 100 per cent modulation, with its associated input system. A broadcast transmitter having a modulator system of this character embodying the invention, is shown in Fig. 5, to which attention is now directed.

Referring to Fig. 4, a radio frequency power amplifier of the class "C" type is indicated at 64 and includes a plurality of electric discharge amplifying devices 65 connected in parallel with a tuned radio frequency input circuit 66, through a coupling device 67 and radio frequency input terminals 68. The output or anode circuit indicated at 69 is also parallel connected with the devices 65 and is coupled with a radiating system 70 through a suitable output coupling device 71.

Audio frequency modulating signals are applied to the anode circuit 69 to modulate it, through a modulator 72, which includes a driver stage 73 and an output stage 74 cascade connected, between audio frequency input terminals 75 and the anode circuit 69.

The audio frequency input terminals 75 are suitably coupled to an input circuit 76 for the driver stage 73 by an audio frequency coupling device or transformer 77. Between the output circuit of the driver stage indicated at 78 and the input or grid circuit of the output stage indicated at 79, a second audio frequency coupling device 80 is interposed and is designed to provide an impedance relation between circuits 78 and 79 substantially like that provided by device 18 in Fig. 1, and for the same purpose.

Likewise between the output circuit of output stage 74, as indicated at 88, and the anode circuit 69, an output coupling device 81 is connected to provide a load impedance arrangement in the output circuit 88 substantially like that provided by device 19 in Fig. 1 and for the same purpose. A radio frequency choke coil 82 and a suitable by-pass condenser 83 serves as a filter to isolate the anode circuit 69 from the modulator 72.

It will be noted that in the output stage 74, the electric discharge devices indicated at 84 are arranged in balanced relation between the input coupling device 80 and the output coupling device 81 in substantially the same manner as in the basic circuit shown in Fig. 1 in connection with devices 16 and 17. The driver stage, however, includes two devices 85 arranged also in balanced relation as distinguished from the single driver tube utilized in Fig. 1.

For greater power output, this arrangement in the driver stage has the advantage that the generated voltage from plate to plate in the output circuit thereof is doubled for a given input voltage between grid and cathode on the output stage, and the step-down ratio of the input coupling device 80 may then be increased by two, or an impedance ratio of four. At the same

time the plate resistance of the driver stage in series with the primary or coupling device 80 is only increased by two. Therefore, the net gain may be one-half of the effective resistance in series with the grid, such for example as resistance R_g of Fig. 4.

In a modulator and a class "C" output amplifier embodying the circuit shown in Fig. 4, tubes known as radiotrons type UV-211 have successfully been employed in the driver stage at 85 with tubes of the type UV-351 used at 84 in the class "B" modulator stage 74, while in the RF power amplifier 64, tubes of the UV-204-A type have been used at 65. These tubes are designated only by way of example, since their characteristics are well known and thereby the values employed in the design of the modulator may more readily be appreciated and understood.

With electric discharge devices of the types named, the coupling device 80 is preferably a step-down transformer having a turn ratio of substantially 5 to 1, or 10 to 1, to each side of the secondary. This provides an impedance ratio of substantially 100 to 1 and with an internal plate impedance R_p in the driver stage of substantially 7000 ohms, thus providing a reflected impedance over through the coupling device 80, in series with the grid circuit 79, of substantially 70 ohms. As compared with the internal impedance R_g of the devices 84 in the output stage, of 800 to 1200 ohms, this impedance is relatively low, as will be seen. The impedance of 800 to 1200 ohms, of course, is measured at a maximum positive potential on the grid which in the present example was substantially 80 volts.

In the output circuit 88 of the class "B" stage 74, the calculated load over from the load circuit 69 is provided by the power amplifier 64 and is substantially 2200 ohms. With an internal impedance of each of devices 84 or r_p of substantially 1400 ohms the coupling or output device 81 is so designed that a turn ratio of one to 1.4 from each side of primary to secondary is provided, and an impedance ratio of one to two. The reflected impedance, R_p , of the load, over into each half of the output circuit 80 is then approximately 1100 ohms, which, as will be seen, is lower than the internal impedance of the output tube associated therewith.

With a modulator of the character described, connected as shown, an output of approximately 1500 watts is obtainable from the two tubes, which is more than sufficient to modulate to 100 per cent the 1,000 watt station, provided by the remainder of the equipment including the RF amplifier indicated at 64. It may be noted that in the modulator shown, the grids of the devices 84 have in practice been driven into the positive range to such an extent that relatively high values of grid current were obtained. For the tubes indicated, this grid current at substantially 80 volts positive, on a positive signal swing reaches as high a value as 140 milliamperes. As this current has to be supplied without an appreciable drop in the signal voltage delivered by the driver stage, it will be appreciated that the direct current resistance of the grid or input circuit 79 must be maintained at a relatively low value, otherwise serious distortion may take place. Likewise, the direct current resistance of the bias potential source must be kept low. It may further be interesting to note that the corresponding power output of the same tubes 84 in a class "A" type of amplifier and at a maximum output rating, is approximately 200 watts. Therefore, the greater

power output from the modulator above described is more readily apparent.

As a practical consideration in the design of the modulator shown and described, the cost of tube equipment was found to be prohibitive when utilizing the usual modulator or class "A" amplifier. For example, to provide the same modulator power output as the two UV-851 tubes in the amplifier described, it was found that between 10 8 and 10 one k. w. tubes would be required in a usual class "A" amplifier, each tube being valued at several hundred dollars. It will, therefore, be appreciated that in the use of an improved class "B" amplifier in a modulator such as that shown 15 and described, a material saving in cost may be effected.

In order to simplify the diagram, the filament or cathode supply circuits have been omitted. The source of cathode current supply, however, is indicated at 86 and is a generator driven by a suitable motor 87. The positive terminal of the generator 86 should be understood as being connected to all of the cathodes, although as above mentioned, the connection lead is omitted. The 20 opposite or negative terminal of the generator is connected thru a common grounded supply lead 90 to all of the cathodes as indicated, and serves as a grounded cathode return lead for all circuits. In practice this connection is provided by making 25 all connections to ground.

Anode or plate potentials for the amplifier tubes 65 and the class "B" modulator tubes 84 are supplied by a suitable high voltage direct current generator 91 thru a positive supply lead 92 having 30 branches 93 and 94, in each of which branches is located a suitable ammeter 95 and 96 respectively. It will be seen from the diagram that the branch 94 supplies the anode circuit 69 in series with the output device 81, while the branch circuit 93 supplies the class "B" modulator tubes 84 thru the usual push-pull circuit arrangement.

A generator 97 in series with generator 91 serves to raise the voltage supplied by the generator 91 to an initial value from which the required potential for operating the above named modulator and amplifier is raised by the generator 91. Generators 91 and 97 are connected in series by a lead 98 and generator 97 is in turn connected with the common ground lead 90 as indicated at 99, where- 45 by the operating anode potentials are applied between the cathode and anodes of the tubes supplied by said generators.

A direct current generator, or generators, are employed in the system of the present example 50 for the reason that they provide good regulation under a varying load condition imposed by the operation of the class "B" amplifier 74. An anode supply source of this character also has a large power capacity.

In the supply of anode potentials to amplifiers of the above character, it will be appreciated that 55 rectified alternating current may be employed. However, certain precautions must be observed to provide good regulation. An alternating current supply means of this character will be de- 60 scribed hereinafter.

The generators 91 and 97 are also driven by a suitable motor 100, and on the same shaft there- 65 with is indicated a third generator 101 which at its positive terminal is connected with the common grounded cathode return lead 90 and which at its negative terminal is connected thru a circuit lead 102 to branch supply leads 103 and 104 to supply a negative biasing potential to the class 70 "B" modulator stage 74 and to the radio fre-

quency amplifier 64. The branch lead 104 is suitably by-passed to the ground lead 90 by a by-pass condenser 105, while in the branch lead 103 for the class "B" modulator, a filter and voltage reducing means is interposed, comprising a series 5 connected resistor 106, a filter choke coil 107 and a by-pass capacitor 108.

The arrangement is such that the grid circuit 19 of the class "B" modulator 74 is isolated from the bias supply 101 by the filter means and the 10 biasing potential is reduced to a desired value. It will be noted that one side of the filter means is connected with the cathode return lead 90 thru a return lead 109 and that between the leads 103 and 109, adjacent to the filter, there is connected 15 a bias voltage supply battery 110. This last is preferably a storage battery or other suitable means for the purpose of providing a stabilizing reservoir of extremely low resistance in the grid circuit return, or in the grid circuit of the class 20 "B" modulator 74. To exactly balance the anode currents of tubes 84, an additional bias adjusting battery or bias means is provided in connection with one tube. In the present example this is a 25 battery 89 in the grid circuit of one tube.

As hereinbefore pointed out, it is essential that the grid circuit be of relatively low resistance and this also includes the source of bias potential, whereby variations in the amount of grid current drawn by the tubes 84 may have no appreciable 30 effect upon the applied signal potentials to cause distortion. This precaution in the other portions of the transmitter is not as essential, hence in the present example a battery reservoir is utilized 35 only in the position shown.

In the driver stage 73 any suitable bias supply means may be employed, and in the present example this may be a simple battery indicated at 40 111. Likewise it should be noted that the source of bias potentials 101 and 110 for the class "B" 45 modulator stage is not limited thereto, but may be provided by any suitable means having a low resistance relative to the resistance of the grid circuit to which it is connected and which is carrying the current drawn by the grid circuit 19.

It is of interest to note that in the circuit shown, the direction of grid current flow, as will be well understood, is in such a direction that it charges 50 the battery 110, tending to maintain it in a charged condition.

The anode or plate potential supply for the driver stage 73 is supplied by the generator 97 thru a tap connection lead 112 between it and the generator 91. A suitable choke coil 113 is interposed in the connection lead 112 which, together 55 with a by-pass condenser 114, provides a filter for the supply of anode potential to the driver stage 73. The anode potential or current supply lead 93 in the modulator stage 74 is also suitably by-passed by a condenser 115. In each case the 60 by-pass connection is to the common grounded cathode supply lead 90.

It will be noted that ammeters 96 and 95 are respectively included in the plate circuit of the class "C" output amplifier 64 and in the output plate circuit of the class "B" modulator 72. In the present example, with no signal being transmitted through the modulator, the plate current may be adjusted to substantially 40 milliamperes, while the plate current through meter 96 is substantially one ampere, with tubes of the UV-851 type at 84 and tubes of the UV-204-A type at 65. A variation in the current through the meter 95, in response to signals may be taken approximately as an indication of the modulation being 70 75

applied to the amplifier 64, since the plate current increases proportionately with an increase in the value of the applied signals.

The plate potential applied to the class "B" amplifier 74 and to the output-amplifier 64 through the supply lead 92 is approximately 2000 volts as delivered by the generators 91 and 97 in series. The potential applied to the plate circuit of the driver stage 73 through the lead 112 is approximately 1000 volts.

The filament potential supplied by the generator 86 is approximately 15 volts. The biasing potential applied to the class "C" output amplifier 64 by the generator 101 is approximately 115 volts. The grid bias employed in connection with the class "B" amplifier stage 74, as provided by the battery 110 and the generator 101 is substantially 80 volts negative, the voltage being reduced from that provided by the generator by the series resistor 106. The biasing potential supplied by the source 111 is that required to operate the devices 85 as normal class "A" amplifiers.

The class "C" amplifier 64 is provided with the usual oscillator circuit in connection with the tuned circuit 66, having a grid leak and condenser combination, 116, in the grid lead and a suitable neutralizing condenser, 117, connected with the plate circuit 69. It will be noted that in each of the individual plate leads there is connected a resistor 118. These are for the purpose of damping out parasitic oscillations in connection with the multiple connected tubes.

The operation is as follows: With the electric discharge devices energized by operation of the supply generators, radio frequency signals from a suitable source are supplied to the terminal 68 of the class "C" radio frequency amplifier 64 and are transmitted through the radiating system 70 as a carrier wave. The value of the signal strength may be measured by a suitable meter 119 in the radiating system.

Audio frequency signals for modulation are applied to the terminals 75 of the modulator 72 and are amplified in the successive stages 73 and 74. The amplified output is supplied to modulate the plate circuit 69 of the amplifier 64 through the coupling means provided by the output device 81. Because of the operation of the devices 84 in the manner hereinbefore described, and because of the result of such operation as described in connection with Fig. 1, a large audio frequency power output is obtained.

While the anode current taken by the devices 84 is maintained at relatively low normal and average values and while the applied anode potentials are within the normal rating of the devices 84, the power output is several times that obtainable from the same devices when used in an ordinary class "A" amplifier. This is for the reason that the impedance of the input circuit in circuit 79 is relatively low, whereby the devices 84 may be driven far into their positive grid bias range without distorting the input wave. At the same time, in the output circuit a load impedance reflected into the circuit 80 is such that the output of the devices 84 is limited only by the space charge or the emission. At the same time the impedance of the load is such that the emission limits of the devices 84 are not exceeded.

A transmitter of this character has the advantage that the radio frequency amplifier and the modulator may be substantially separate units as shown, and may be coupled for plate circuit modulation by an isolating coupling device such as a transformer. Furthermore, by the

proper design of the input and output coupling devices of the output stage of the modulator, the amplifier devices employed therein may be driven far beyond their normal useful range of operation to produce a power output many times in excess of that ordinarily provided, thereby materially reducing the cost of manufacture and operation of a transmitter for a given power output. As class "C" radio frequency amplifiers are primarily plate circuit modulated and the class "B" amplifier of the present invention is adapted to operate in connection with various loads by the choice of a suitable impedance matching means, such as a transformer, the class "B" amplifier of the present invention is particularly well adapted for use in combination with the class "C" type of amplifier employed in transmitters.

Referring now to Fig. 5, a transmitter having a modulation system provided by a class "B" modulator embodying the invention, is shown in connection with an alternating current source of operating potentials.

In the transmitter shown in Fig. 5, the radio frequency system includes a crystal oscillator 145 followed by two cascade connected radio frequency amplifiers 146 and 147 which drive a class "C" radio frequency output amplifier 148. The class "C" amplifier, like that shown in Fig. 5, is plate circuit modulated and for this purpose is provided with a plate current connection 149 in 30 which is located an indicating ammeter 150 and a radio frequency filter means including a choke coil 151 and a suitable by-pass condenser 152 adjacent to the amplifier.

Audio frequency modulation is applied to the circuit 149 from a class "B" amplifier 153 constructed after the manner of that shown in Fig. 1, and connected to the circuit 149 after the manner of that shown in Fig. 5. For this purpose, the amplifier is provided with an input coupling device 154 providing a low impedance input circuit and an output coupling device 155 providing a low impedance output circuit, between which are connected in balanced relation, the class "B" amplifier devices 156.

In common with lead 149 the anode circuit of devices 156 receives its operating current or potential from a supply lead 157, and biasing potentials are supplied by a suitable source 158. Audio frequency signals are supplied to the input coupling device 154 from a suitable source indicated at 159. This may be a speech amplifier as indicated. Direct current anode potentials are delivered to supply lead 157 from an alternating current source indicated by terminals 160, thru a suitable full wave rectifier 161 which includes a pair of cathode rectifier devices 162.

The cathodes of the device 156 and the devices 162 are heated from the source 160 thru a separate transformer 163 which permits the cathodes to be separately heated before the anode potential supply is excited. For this purpose, a separate switch 164 is provided for the cathode heating transformer 163 and another switch 165 is provided for energizing the rectifier 161.

The positive and negative supply leads 166 and 167, respectively, from the rectifier are connected with the cathodes of devices 156 and with the positive supply lead 157. In one of the leads, preferably in the positive supply lead 166, is connected a choke coil 168 in association with a suitable by-pass condenser 169, whereby the desired regulation is obtained under load conditions imposed by the devices 156. The operation of the filter means provided by the choke coil 168 and 75

by-pass condenser 168 will hereafter be considered.

The coupling device 155 should preferably be designed to couple the devices 156, which may be of the radiotron UV-203-A type, as class "B" audio amplifiers for a maximum anode current of approximately 400 milliamperes for the type of tubes above mentioned, and operated at approximately 1000 volts. Such a loading permits approximately maximum output of the class "B" amplifier. Higher currents to the class "C" amplifier will result in an overloading of the class "B" tubes 156. It should be noted that during a peak modulation of 100 per cent the input power to the plates of the class "C" amplifier 148 increases 50 per cent so that the plate dissipation increases by the same percentage. However, the plate current to the class "C" tubes as indicated by the meter 150, will remain steady so that care must be taken not to exceed the tube rating.

If a maximum output is desired from the modulator 153, medium power tubes should be used in the output stage of the speech amplifier 159 to excite the class "B" tubes 156 thru the coupling device 154.

It will be noted that a resistor 170 is employed in the anode circuit of each of the devices 156. These may be of a value of approximately 30 40 ohms, for example, and serve to prevent any high voltages because of high oscillations, or surges in the plate circuits of the class "B" tubes. The radio frequency choke coil 151 and the condenser 152 prevent radio frequency currents from entering the transformer 155. The "C" battery 158 for the class "B" tubes, is adjusted to such a value that each tube draws a normal plate current of approximately 20 to 30 milliamperes for the type of tubes above mentioned, this being substantially plate current cut off for such tubes. The battery 158 represents any suitable source of "C" bias having a low resistance as described in connection with the preceding embodiment of the invention, and is preferably a heavy duty type of "B" battery.

A meter 171 is placed in circuit with the anodes of the devices 156. As the maximum plate current to a class "B" audio frequency modulator or amplifier depends upon the power output, the variations of the meter 171 may be taken as a fair indication of the percentage modulation.

It will be noted that the secondary of the output coupling device 155 is arranged in two sections 172 and 173, whereby the sections may be connected in series, or in parallel as shown. The type of connection depends upon the type of tubes used in the class "C" radio frequency amplifier 148. For lower plate currents at higher voltages the series connection may be used, while for higher plate currents and lower voltages the parallel connection may be used.

It will be noted that the rectifier 161 or anode supply circuit of which it forms a part, is the usual type of full wave rectifier. However, the filter reactor 168 is a special design to improve regulation, and the filament transformer 163 is separate from that of the rectifier 161 so that hot cathode mercury vapor tubes may be employed at 162 and heated before the plate supply switch at 165 is closed. During silent periods of operation of the transmitter, the filaments of all of the tubes may be left on while the plate supply is turned off, thereby requiring a minimum time to start when placed again in operation.

With reference to the filters 168 and 169, the

inductance 168 is preferably of the iron core type in series, as shown, with the rectifier source, and is tuned as by the condenser 169 to a frequency such as the second harmonic being 120 cycles for a 60 cycle supply circuit. An indicated 5 in the drawings, there should be no filtering between the rectifier and the resonant filtering element because it is arranged to operate upon an appreciable alternating current component. Any additional filter means, such as a shunt condenser 10 174, may be added in the anode supply circuit following the filter shown, altho none is necessary in the supply circuit of the present example.

The circuit arrangement is such that in connection with the filter, an increase in the current 15 taken by the load or by the class "B" amplifier 153 in the present example, de-tunes the tuned filter element and results in a tendency to raise the voltage across the output of the supply source 20 because of a drop in the impedance to the unfiltered alternating current component. The 120 cycle component is selected as the strongest of the available harmonics of the supply source.

It is preferable also that the choke coil 168 should be so designed that normally sufficient current may flow thru the choke coil to bring it near to its saturating point, since a change of reactance for regulation purposes must be proportional to an increase in the load current. The tuning condenser 169 may be omitted if the reactor is so designed that its impedance decreases rapidly with an increase in direct current.

In operation, the regulation is aided somewhat by providing for a normal load current, or from 10 to 20 per cent of the output current derived 35 from the plate supply source. With this normal load current, the filter is tuned until the inductance offers a maximum impedance at the chosen frequency which reduces the output voltage to a minimum.

The choke coil is also designed so that it tends to saturate as the load current is increased so that it tends to introduce a lower reactance in the circuit for greater load currents, while at the same time the change in reactance de-tunes the circuit, 45 which also tends to sharply reduce the impedance of the circuit to maintain the tube voltage more nearly constant regardless of the tube current within the power range of the plate supply means. The condenser 174 functions as a normal filter 50 condenser and should be relatively large to effectively by-pass the a. c. components to currents to the class "B" modulator.

While the invention has been illustrated and described for purposes of convenience in its present application to audio frequency amplifiers generally, and in systems for the modulation of high power transmitters, it is obvious that it is not limited thereto, but may be applied to any electrical apparatus requiring large quantities of 60 fluctuating electric power, without involving costly and complicated equipment including a large number of amplifier devices and associated potential supply apparatus.

I claim as my invention:

1. The combination with a radio frequency vacuum tube amplifier, having an anode circuit, of means for supplying audio frequency power to said anode circuit, said means including an audio frequency amplifier having a balanced audio frequency input circuit and a balanced audio frequency output circuit, an impedance changing device interposed between said last named circuit and the first named anode circuit as a coupling device, the coupling ratio being such that the out- 75

put circuit operating impedance is less than the internal impedance of said amplifier, and the input circuit having an impedance which is lower than the lowest input operating impedance of said 5 amplifier, whereby the power output may be proportional to the square of the input potential.

2. The combination with a radio frequency power amplifier, having an anode circuit, of means for supplying audio frequency power to said anode 10 circuit, said means including an audio frequency amplifier having a balanced audio frequency input circuit and a balanced audio frequency output circuit, an impedance changing device interposed between said last named circuit and the 15 first named anode circuit as a coupling device, the coupling ratio being such that the output circuit alternating current impedance is less than the internal impedance of said amplifier, and the input circuit having an alternating current 20 impedance which is lower than the lowest input operating impedance of said amplifier when drawing a predetermined maximum grid current, whereby the power output may be proportional to the square of the input potential.

25 3. In a radio transmitting system, the combination with a radio frequency output amplifier of the type having a power output which varies as the square of the anode potential within predetermined limits, and an anode circuit therefor, of an audio frequency amplifier means for applying audio frequency power to said anode circuit, said means including a pair of electric discharge devices each having an anode, a cathode, and a control grid, said devices being connected in balanced relation to each other and being arranged to provide a power output proportional to the square of the excitation grid voltage, an input circuit of low impedance with respect to the grid impedance of each of said devices when drawing 40 a predetermined maximum grid current, an output circuit of low impedance with respect to the anode impedance of each of said devices, said output circuit including an output coupling device connected with said first named anode circuit, and means for applying audio frequency signal potentials to said input circuit.

45 4. In a radio transmitting system, the combination with a radio frequency output amplifier of the type having a power output which varies as the square of the anode potential within predetermined limits, and an anode circuit therefor, of an audio frequency amplifier means for applying audio frequency power to said anode circuit, said means including a pair of electric discharge devices each having an anode, a cathode, and a control grid, said devices being connected in balanced relation to each other and being arranged to provide a power output proportional to the square of the excitation grid voltage, an input circuit of low alternating current impedance with respect to the grid impedance of each of said devices when drawing a predetermined maximum grid current, an output circuit of low alternating current impedance with respect to the anode impedance of each of said devices, said output circuit including an output coupling device connected with said first named anode circuit, and means for applying audio frequency signal potentials to said input circuit.

50 5. Means for plate modulating a class C radio frequency amplifier comprising an audio frequency amplifier transformer coupled to the plate circuit of said first named amplifier, a radio frequency filter means interposed in said plate 55 circuit between said transformer and said class C

amplifier, and a speech amplifier coupled to the input circuit of said class B audio frequency amplifier, said first named amplifier having a balanced audio frequency input circuit and a balanced audio frequency output circuit, and having 10 input and output circuits provided in connection with said transformer coupling and said speech amplifier coupling the operating impedances of which input and output circuits are less, respectively, than the lowest internal operating input 15 and output impedances of said devices when drawing a predetermined maximum grid current.

6. Means for plate modulating a class C radio frequency amplifier comprising a class B audio frequency amplifier transformer coupled to the 15 plate circuit of said first named amplifier, a radio frequency filter means interposed in said plate circuit between said transformer and said class C amplifier, a speech amplifier, and means for coupling said class B audio frequency amplifier to the speech amplifier comprising a step-down coupling transformer providing in the input circuit of said class B amplifier an alternating current impedance lower than the lowest input impedance of the amplifier when drawing 20 maximum grid current, and an output coupling transformer for the class B audio frequency amplifier having impedance changing windings adapted for series and parallel connection in the 25 plate circuit of the class C amplifier.

30 7. A modulator for a radio frequency amplifier comprising a push-pull class A amplifier stage, a balanced second stage amplifier coupled to said class A amplifier stage, of the class B audio frequency type comprising a pair of balanced electric 35 discharge amplifier devices and including a step-down input transformer and a step-down output transformer, the coupling ratios of said transformers and the impedances in circuit therewith being such that the output circuit operating impedance is less than the internal impedance of said second stage amplifier, and that the input circuit impedance is lower than the lowest input operating impedance of said second stage amplifier, means for supplying modulation signals to 40 the input circuit of said first stage amplifier, and a radio frequency amplifier having an anode circuit coupled to the output of the class B stage 45 through said output transformer.

8. A modulator for a radio frequency amplifier 50 comprising a push-pull class A amplifier stage, a balanced second stage amplifier of the class B audio frequency type comprising a pair of balanced electric discharge amplifier devices and including a step-down input transformer and a 55 step-down output transformer, the coupling ratios of said transformers and the impedances in circuit therewith being such that the output circuit operating impedance is less than the internal impedance of said second stage amplifier, and that 60 the input circuit impedance is lower than the lowest input operating impedance of said second stage amplifier, and means for supplying modulation signals to the input circuit of said first stage amplifier, and said output stage including 65 a grid circuit through which grid current flows in response to signal currents and a storage battery connected in said grid circuit to supply substantially constant grid potentials thereto and to be charged by the flow of grid current.

9. In a radio transmitting system, the combination of a radio frequency amplifier comprising a plurality of parallel connected electric discharge amplifier devices having a grid circuit and an anode circuit, means for supplying radio fre- 75

quency signals to said grid circuit, means for coupling said anode circuit to radiate signals, said grid and anode circuits being tuned, a modulation input transformer connected in the low potential side of the anode circuit of said first named amplifier, a radio frequency filter interposed between said transformer and said first named amplifier in the anode circuit thereof, a balanced modulation signal electric discharge amplifier connected with said transformer, said amplifier being an audio frequency power amplifier comprising a pair of electric discharge amplifier devices having balanced low impedance input and output circuits, the impedances of which circuits are lower than the lowest corresponding input and output impedances of said amplifier devices when drawing a maximum predetermined grid current and said devices being arranged to operate alternately, a balanced electric discharge driver stage for said amplifier and means for supplying modulation signals to said driver stage.

10. Means for plate modulating a class C radio frequency amplifier comprising a class B audio frequency amplifier transformer coupled to the plate circuit of said first named amplifier, a radio frequency filter means interposed in said plate circuit between said transformer and said class C amplifier, a speech amplifier, and means for coupling said class B audio frequency amplifier to the speech amplifier comprising a step-down coupling transformer, said class B amplifier being of the audio frequency type comprising a pair of electric discharge amplifier devices having balanced input and output circuits the operating impedances of which are lower at all times than the lowest corresponding input and output impedances of said devices when drawing a maximum predetermined grid current and said devices further being arranged to operate alternately.
